(57) **CLAIM**

The ornamental design for a display screen or portion thereof with graphical user interface, as shown and described.

DESCRIPTION

The sole FIGURE illustrates a front view of a display screen or portion thereof with graphical user interface showing my new design.

The outermost broken line rectangle illustrates a display screen or portion thereof with graphical user interface that forms no part of the claimed design. The remaining broken lines within the outermost broken line rectangle illustrate portions of the graphical user interface that form no part of the claimed design.
